UNITED STATES PATENT OFFICE.

JOHN CASSIDY, OF CAMBRIDGE, MASSACHUSETTS.

CLOG.

SPECIFICATION forming part of Letters Patent No. 258,218, dated May 23, 1882.

Application filed February 20, 1882. (No model.)

To all whom it may concern:

Be it known that I, JOHN CASSIDY, of the city of Cambridge, in the county of Middlesex and State of Massachusetts, have invented a new and useful Improvement in Clogs, of which the following is a full, clear, and exact description, reference being had to the accompanying drawings, in which like letters indicate corresponding parts.

10 Figure 1 is a vertical section of the clog, in which is represented the pyrotechnic device, consisting of the principal parts B and C. Fig. 2 is a section of the heel of the clog. Fig. 3 is a vertical section of the front side of the 15 heel of the clog. Fig. 4 is a section of the device C B z y, end view. Fig. 5 is a section representing a side view of the same parts enlarged from Fig. 1.

The object of my invention is to make a 20 clog with a self-adjusting device for discharging percussion-caps, torpedoes, or similar explosives while in use, at the will of the wearer of the clog.

It is evident that the discharge of torpedoes, percussion-caps, or similar explosives by 25 some simple device under the control of the wearer, and which can be operated without interference with the ordinary use of the clog, must materially add to the display and pleasurable sensation evoked by the dancer. Therefore, to effect this most desirable result, I form 30 the clog of the upper A, the lining d, and the thick sole b, with a high heel, a. In order to make the clog light, I place between the sole b and the upper-lining d a piece of cork or similar 35 material, (represented by c.) This also gives elasticity to the sole and ease to the wearer in use. Through the sole b, I pass the rod B, having a small knob or button upon its end, x', 40 attached to the rod B by a swivel-joint. The opposite end of the rod B is bent as shown in x. Just forward of the heel I support a circular sleeve, C, by the connection x². The sleeve C is formed with teeth or inclines or bevels 45 upon either end, as represented by y. The part C is stationary, being supported by the connection x² with the sole of the shoe b. The rod B revolves inside of the stationary cylinder C. Upon the rod B, I place the studs z z, 50 one upon each side of the cylinder C. The caps or other explosives are represented by e e,

and are placed upon the heel of the clog, as shown in Figs. 2 and 3.

The discharging device is operated as follows: The wearer strikes or presses the rod B upon the knob x', which presses the rod longitudinally toward the heel. The stud z, engaging with one of the teeth y, follows the incline of the tooth, and thus turning the rod B the distance represented by the incline of the tooth. 55 The rod B is then sprung back to its place by means of the spring y'. In returning to its position the teeth upon the opposite side of the cylinder C, toward the heel, are so formed that the stud upon that side, z, engages one of the 60 teeth of the cylinder, and, following the incline as the rod B is drawn back, continues the turning of the rod B, as already explained, in pressing it in by striking upon x'. The rod B is now in position to be struck again upon the knob x', 65 and the teeth opposite to the forward stud, z, are in a proper position to act upon the stud and partially turn the rod, as already described. Thus by striking or pressing upon the knob x' the rod B is revolved, and the bent end of 70 the rod x is projected against the parts e e, following in succession the circle of explosives, as represented in Fig. 3.

The operation of pressing upon the rod B is to turn the rod and to explode the percus- 80 sion-caps, placed as represented in Fig. 3. Of course it is obvious that this same principle and substantially the same mechanical device may be used for the same purpose in some other form or placed upon some other part of the 85 clog. For instance, my device may be placed so as to be struck from the heel instead of from the toe of the clog, or from the side. The position where the device is operated is immaterial. I preferably make an orifice through the 90 heel, as represented by dotted line from e to k, Fig. 2. By this means the fire or flash of the explosives is seen at k. This is a very attractive addition to the effect produced by my pyrotechnics and discharging mechanism, as here- 95 fore described.

Having now described my invention, what I claim, and desire to secure by Letters Patent of the United States, is—

1. A clog having a holding device in the 100 breast of the heel for explosives, and a discharging device attached to the sole, and

adapted to operate substantially as and for the purposes specified.

2. In a clog, the rod B, knob x' , spring y' , and the studs $z z$, in combination with the cylinder C, having teeth or inclines upon each side, $y y$, substantially as and for the purposes set forth.

3. A clog provided with explosives arranged in a circular position upon the heel, in combination with a discharging mechanism attached to the sole of the clog, all adapted to be operated substantially as and for the purposes set forth.

4. The combination of the clog A, having a sole, b , and heel a , with the pyrotechnic discharging device B, with button x' , spring y' ,

studs $z z$, and the bent end x , the said rod adapted to revolve in a stationary cylinder, C, said cylinder having a row of projecting teeth or inclines upon either end, placed to relatively 20 operate upon the studs $z z$ to turn the rod B, all arranged, combined, and operating substantially as and for the purposes set forth.

5. The combination of a clog provided with a holding device for explosives, and a dis- 25 charging device attached to the clog, all operating substantially as and for the purposes set forth.

JOHN CASSIDY.
